HOLD-DOWN BRACKET

Fred J. Burns, Saginaw, Mich., assignor to The Columbia Mills, Inc., New York, N. Y.

Application January 24, 1947, Serial No. 724,085

9 Claims. (Cl. 160—328)

1

This invention relates to brackets in general, and more specifically to hold-down brackets for releasably securing the free end of frameless window screens to a window sill.

One of the prime objects of the invention is to design a very simple, practical, and inexpensive bracket which can be readily manufactured and assembled, and which can be formed of stampings so that it lends itself to mass production.

Another object is to design an easily operable, compact, hold-down bracket having screen bar guiding and holding means formed integral therewith for guiding the screen bar and releasably locking it in position.

A further object is to design a hold-down bracket formed with slotted openings to accommodate the locking lever and to permit it to be swung to fully locked position.

To the accomplishment of the foregoing and related ends, said invention then consists of the means hereinafter fully described, and particularly pointed out in the claims, the annexed drawing and following description setting forth, in detail, certain means and one mode of carrying out the invention, such disclosed means and mode illustrating, however, but one of various ways in which the principle of the invention may be used.

In the drawing:

Fig. 1 is a fragmentary view showing my hold-down bracket mounted on a window sill and associated with a frameless window screen, the solid lines showing the bracket in locked position and the broken lines showing it in unlocked position.

Fig. 2 is a perspective view of one of my hold-down brackets, with the locking lever in raised position.

Fig. 3 is a view similar to Fig. 2 showing the locking lever swung down to locked position.

Fig. 4 is a side-elevational view, the locking link being shown in section.

Brackets of the type shown in the instant application must be light, smooth, easily operable, and of neat and pleasing appearance, because they are mounted in places where they are clearly visible; fabrics come into contact therewith, and they must be easily operable by the housewife, cleaners, and others working around and in connection with windows and screens, and I have, therefore, designed a stamped bracket, streamlined in appearance, and which is readily and easily operable when desired.

Referring now to Fig. 1 of the drawing in which I have shown a fragmentary portion of a window frame W, the frame opening being closed by a

2

frameless screen S having a sheet metal strip or bar 5 secured on the lower end thereof, and which is adapted for releasable engagement by the hold-down bracket B in substantially the same manner as shown and described in my application for U. S. Patent on Frameless window screens, Serial No. 712,861, filed November 29, 1946.

The bracket B is preferably, but not necessarily, in the form of a stamping, and the main vertical body portion is angular in cross section to form wings 6 and 7. A U-shaped section 8 is formed integral with the lower end of the wing 7 and accommodates the end bar 5 of the frameless screen S, the outer leg 9 of said U-shaped section being shorter than the inner leg to permit insertion and/or removal of the bar 5 from the brackets.

Laterally projecting clips 10 are welded or otherwise secured to the inner face of the bar 5 and are adapted for engagement by the locking link 11 of the bracket, and in a manner to be described.

The locking lever 12 is also in the form of a stamping; it is U-shaped in cross section, with the lower end flattened as at 13 for easy engagement by the fingers of the operator. The inner end of the lever is bifurcated as at 14 and a pin 15 serves to pivotally connect the lever to the upper end of the wing 6 of the standard.

The stamped locking link 11 is hingedly connected to the locking lever 12 at a point spaced from the pin 14 by means of the pin 16, and a similar pin 17 connects the lower end of the link to the wing section 6 of the body, said pin being mounted in a vertical slot 18 formed in said wing to provide for the necessary vertical movement of the pin when the lever is swung to move the link into engagement with the clip.

The lower end of the link 11 is bent outwardly as shown and forms a jaw section 20 which is adapted for engagement with the clip 10 when the members are in assembled relation, and the lever is swung down to locking position, the bar 5 being forced down into tight insect and weather-proof engagement with the sill L of the window.

A transversely disposed channel 21 is formed in the wing 6 of the standard, and accommodates the pin 16 when the lever 12 is swung to fully locked position, and as clearly shown in Fig. 3 of the drawing.

Screw openings 22 are provided in the walls of the U-shaped section of the bracket to facilitate mounting it in position, the leg 9 of the U-shaped

portion permitting insertion or removal of the bar 5 when the lever is in raised position.

While in the instant application I have shown the bracket associated with a frameless window screen, it will be understood that this is for explanatory purposes only as the bracket can be used to secure other articles as desired.

From the foregoing, it will be obvious that I have perfected a very simple, practical, economical and neat-appearing holdown bracket for holding and releasably locking frameless window screens and similar articles in position.

What I claim is:

1. A holdown bracket of the class described comprising vertically disposed body portion 15 mounted on a support formed with an offset U-shaped section adapted to accommodate a member to be secured, and a compound lever and a link assembly pivotally mounted on said body and engageable with said member for locking it when the lever is swung to locked position.

2. The combination as defined in claim 1 in which the link is pivotally connected to the locking lever at a point spaced from the pivot point thereof, and has slidable engagement with said body, said lever forcing the end of the link into engagement with said member when the lever is swung down.

3. The combination as defined in claim 1 in which a horizontally disposed slot is provided in the body portion to facilitate full locking movement of the locking lever.

4. The combination as defined in claim 1 in which the U-shaped section automatically holds the article to be secured in cooperative relation with the locking link of the holdown bracket.

5. A holdown bracket of the class described comprising, a stamped standard having a U-shaped section formed integral therewith and adapted to accommodate a member to be secured, a stamped locking lever pivotally connected to

the upper end thereof, a vertical slot in said standard, a link pivotally connected to said lever at a point spaced from the pivot point of the lever with its lower end slidably mounted in said slot, and a jaw formed on the lower end of said link for engagement with the member to be secured when the locking lever is swung down.

6. The combination as defined in claim 5 in which the standard is angular in cross section and the locking link is U-shaped to accommodate one wing of the standard therebetween.

7. The combination as set forth in claim 5 in which the outer leg of the U-shaped section is shorter to facilitate insertion of the member to be secured.

8. The combination as defined in claim 5 in which the link is U-shaped in cross section with the lower end of one of the legs bent laterally to form a jaw.

9. A holdown bracket of the class described, comprising, a vertically disposed body member angular in cross section and forming wings, a locking lever secured to the upper end of one of said wings, a locking link pivotally secured to said lever at a point spaced from said pivot point, with its lower end slidably connected to said wing, and an offset jaw formed on the lower end of said link for locking engagement with a member to be secured.
